UNITED STATES PATENT OFFICE

123,351

DESIGN FOR A DOILY OR SIMILAR ARTICLE

Kenneth C. Hamilton, Milwaukee, Wis., assignor to Milwaukee Lace Paper Company, Milwaukee, Wis., a corporation of Wisconsin

Application February 26, 1940, Serial No. 90,521

Term of patent 14 years

To all whom it may concern:

Be it known that I, Kenneth C. Hamilton, a citizen of the United States, residing at Milwaukee, in the county of Milwaukee and State of Wisconsin, have invented a new, original, and ornamental Design for a Doily or Similar Article, of which the following is a specification, reference being had to the accompanying drawing, forming a part thereof.

The single figure of the drawing is a plan view of a circular doily embodying my new design.

The essential or dominant feature of the design resides in the lace border, shown in full lines in the drawing, which border continues around the edge of the doily, as indicated by the dotted lines in the drawing.

The design, as here shown, is applied to a doily, but it is also applicable to similar articles, such as table-cloths, bedspreads, napkins, handkerchiefs, and the like.

I claim:

The ornamental design for a doily or similar article, substantially as shown and described.

KENNETH C. HAMILTON.
